SELF-PROPELLED MINE ROOF PROP

Paul J. Malloy, Lakewood, Ohio, assignor of one-half to Paul V. Malloy, Lakewood, Ohio

Application August 16, 1951, Serial No. 242,159

9 Claims. (Cl. 61—45)

1

This invention relates to mining apparatus and, more particularly, to mine roof supports or prop devices.

An object of the present invention is to provide a novel prop device which is of a simple and economical construction involving a relatively small number of parts, but which is very rugged and durable and can be readily manipulated for engaging the same with or disengaging the same from the mine roof.

Another object is to provide a novel prop device of this character which comprises adjacent prop units and is movable along the mine floor in response to a relative step-by-step movement between the prop units, and in which the movement of the prop device is preferably a self-propelled movement.

A further object is to provide a novel prop device of the character mentioned in which the adjacent prop units comprise, respectively, a pair of spaced jacks and a third jack disposed between the spaced jacks, and in which an actuating means for the prop units imparts pushing and pulling forces thereto for causing the step-by-step advance movement of the prop device.

As still another object, this invention provides a novel prop device of the kind above referred to in which each of the prop units comprises floor and roof engaging members and an actuating means for the roof engaging member including cooperating inclined wedging surfaces.

The invention can be further briefly summarized as consisting in certain novel combinations and arrangements of parts hereinafter described and particularly set out in the claims hereof.

In the accompanying sheets of drawings,

Fig. 1 is a side elevation showing a prop device embodying the present invention, the device being shown in its longitudinally contracted condition;

Fig. 2 is a top plan view of the prop device in the same longitudinally contracted condition;

Fig. 3 is another side elevation similar to Fig. 1 but showing the prop device in a longitudinally extended condition;

Fig. 4 is a top plan view of the prop device in such longitudinally extended condition;

Fig. 5 is a longitudinal vertical section taken through the prop device substantially as indicated by section line 5—5 of Fig. 2;

Fig. 6 is a similar longitudinal sectional view taken as indicated by section line 6—6 of Fig. 2; and

Fig. 7 is a transverse vertical section taken

2

through the prop device as indicated by section line 7—7 of Fig. 1.

As one practical embodiment of this invention, the drawings show the novel prop device 10 as comprising a pair of longitudinally extending adjacent prop units 11 and 12. The prop unit 11 comprises a pair of longitudinally extending jacks 13 and 14 which are disposed in adjacent substantially parallel relation with a longitudinal space 15 therebetween. The prop unit 12 comprises a single longitudinally extending jack located between the spaced jacks 13 and 14 of the prop unit 10. The space 15 constitutes a working space for the intermediate prop unit or jack 12.

As shown in Figs. 1, 5 and 7, each of the jacks 13 and 14 of the prop unit 11 comprises a lower or floor engaging member 16 adapted to be supported on the mine floor 17 and an upper or roof engaging member 18 which is engageable with the mine roof 19 in the manner explained hereinafter. The members 16 and 18 are in the form of blocks which can be constructed of wood, as for example wood timbers, or any other suitable material. The floor members 16 of the jacks 13 and 14 are preferably provided on the bottom surface thereof with metal skid plates or shoes 20 to facilitate sliding movement of the prop unit 11 on the mine floor 17.

Each of the jacks 13 and 14 also embodies a wedging means for causing movement of the roof member 18 into and out of engagement with the mine roof 19. This wedging means is here shown as comprising inclined wedging surfaces 21 and 22 provided on the adjacent faces of the floor and roof members 16 and 18 and which wedging surfaces are in sliding cooperation with each other. The wedging surfaces 21 and 22 can be formed by the inclined faces of the floor and roof members 16 and 18, but preferably, are formed by metal plates or bearing strips 21^a and 22^a provided on such inclined faces to facilitate relative sliding therebetween.

From the construction thus far described for the jacks 13 and 14, it will be seen that the roof member 18 is itself a substantially wedge-shaped member which will be lifted and will engage the mine roof 19 with a powerful lifting force in response to movement of this member toward the left as seen in Fig. 1, that is, in response to an uphill sliding movement of this member relative to the floor member 16 which is likewise a substantially wedge-shaped member. During such uphill movement of the member 18 to engage the same with the mine roof 19, the

inclined surface 22 slides on the inclined surface 21 of the floor member 16 in wedging cooperation therewith. Movement of the roof member 18 in a downhill direction relative to the floor member 16, that is, toward the right as seen in Fig. 1 disengages the roof member from the mine roof 19 and releases the lifting or supporting force being applied thereto.

For causing such uphill and downhill relative movements of the roof member 18 relative to the floor member 16 of the jacks 13 and 14, each of these jacks is provided with a power device which is here shown as being in the form of a hydraulic cylinder 24. The adjacent surfaces of the floor and roof members 16 and 18 of these jacks have channel-shaped recesses therein in substantially registering relation which define an operating chamber 25 for the hydraulic cylinder 24. One end of this hydraulic cylinder is pivotally anchored on one of the jack members, in this instance the floor member 16, by means of a transverse anchor pin 26. A piston 27 reciprocably operable in the cylinder 24 is connected with the inner end of a piston rod 28 which projects from the cylinder. The outer end of the piston rod is pivotally connected with the roof member 18 by means of a transverse pivot pin 29.

The cylinder 24 is a double-acting cylinder to which hydraulic fluid under pressure is adapted to be supplied by conduits 30 and 31. The above-mentioned uphill movement of the roof member 18 of the jacks 13 and 14 relative to the floor member 16 is produced by supplying hydraulic fluid under pressure to one end of the cylinder 24 through the conduit 31 and releasing hydraulic fluid from the opposite end of the cylinder through the conduit 30. The downhill movement of the roof member 18 relative to the floor member 16 is produced by supplying hydraulic pressure fluid to the cylinder 24 through the conduit 30 and releasing pressure fluid from the other end of the cylinder through the conduit 31. During such uphill and downhill actuations of the roof member 18, the cylinder 24 will swing on the pivot pin 26 as is represented by the dotted line cylinder positions 24^a and 24^b shown in Fig. 1.

The single jack constituting the prop unit 12 also comprises a pair of floor and roof members 33 and 34, similar to the floor and roof members 16 and 18 described above, and of which the member 33 is supported on the mine floor 17 and has a skid plate 35 on the bottom thereof to facilitate sliding of this prop unit on the mine floor. The roof member 34 is movable into and out of engagement with the mine roof 19 in the same manner as the member 18 of the jacks 13 and 14. That is to say, the floor and roof members 33 and 34 of the prop unit 12 have cooperating inclined wedging surfaces 36 and 37 on their adjacent faces and formed by metal bearing plates or strips 36^a and 37^a and which wedging surfaces are in sliding cooperation with each other.

The uphill and downhill movements of the roof member 34 of the prop unit 12 are produced by an actuating device embodied in this unit and which is here shown as being in the form of a double-acting hydraulic cylinder 38 having a piston 39 reciprocably slidable therein. The cylinder 38 is located in a chamber 40 which is formed by registering recesses in the adjacent portions of the floor and roof members 33 and 34.

One end of the hydraulic cylinder 38 is connected with the floor member 33 by means of a

transverse pivot pin 41. A piston rod 42 connected with the piston 39 has its outer end connected with the roof member 34 by means of a transverse pivot pin 43. Uphill movement of the roof member 34 relative to the floor member 33 is produced by supplying hydraulic pressure fluid to the right end of the cylinder 38 through the conduit 44 and downhill movement of the roof member 34 is produced by supplying pressure fluid to the opposite end of the cylinder through the conduit 45. During such uphill and downhill movements of the roof member 34 the cylinder 38 swings to its inclined dotted line positions 38^a and 38^b as shown in Fig. 6.

15 The prop unit 11 also includes a connecting means for the spaced jacks 13 and 14 which holds these jacks in the spaced relation shown in the drawings such that they will move together during actuation of this prop unit along the mine floor 17. This connecting means is here shown as comprising a transverse bar 47 located at one end of the prop device 10 and formed by a pair of upper and lower bar members or channels 47^a and 47^b. The forward ends of the floor members 16 of the jacks 13 and 14 are connected with the transverse bar 47 by means of the yokes 48. These yokes are here shown as being in the form of strap members having an eye portion 48^a at the rear end thereof and a flat portion 48^b at the front end thereof which is clamped between the upper and lower members 47^a and 47^b of the transverse bar 47 by a clamping bolt 49. The rear ends of the yokes 48 are connected with the floor members 16 of the jacks 13 and 14 by transverse anchor pins 50.

30 The prop device 10 also includes an actuating means for causing relative reciprocating movements between the prop units 11 and 12 which produces a self-propelled step-by-step advance movement of the prop device along the mine floor 17 as will be more fully explained hereinafter. This actuating means also constitutes a connecting means between the prop units 11 and 12 and is here shown as comprising a hydraulic power cylinder 52. In this instance the actuating means is located in the prop unit 12, although if desired, it could be embodied in one or both of the jacks of the prop unit 11. To accommodate the hydraulic cylinder 52, the floor member 33 is provided with a longitudinal passage or recess defining a chamber 53 in which this cylinder is disposed.

35 One end of the hydraulic cylinder 52 is connected with the floor member 33 by means of a transverse anchor pin 54. A piston 55 is reciprocable in the cylinder and is connected with the inner end of a piston rod 56. The outer end of the piston rod 56 is connected with the transverse bar 47 at an intermediate point thereof by means of the clamping bolt 57. Conduits 58 and 59 are connected with the cylinder 52 adjacent the opposite ends thereof for supplying hydraulic pressure fluid to this cylinder and exhausting such fluid therefrom.

40 When the prop device 10 has been placed in a desired location in a mine room or tunnel passage, it can be expanded into supporting engagement with the mine roof by causing the above explained uphill movements of the roof members 18 and 34 of the prop units 11 and 12 relative to the floor members 16 and 33 of these prop units. When it is desirable to advance the prop device to a different position, it is caused to propel itself along the mine floor 17 in the manner 45 which will now be described. As a preparatory

step to such advance movement, the roof member or members of one of the prop units, for example, the roof members 18 of the jacks 13 and 14, are disengaged from the mine roof 19 while the roof member 34 of the prop unit 12 remains in its roof engaged position.

By supplying pressure fluid to the hydraulic cylinder 52 through the conduit 58, this cylinder is now actuated to apply a pushing force to the transverse bar 47 which, in turn, will apply a pulling force to the jacks 13 and 14 and will advance the same to the position shown in Figs. 3 and 4 by sliding the floor members 16 thereof along the mine floor. When the prop unit 14 has been thus advanced relative to the prop unit 12, the hydraulic cylinders 24 of the jacks 13 and 14 are then actuated in a direction to cause an uphill movement of the roof members 18 to engage the same with the mine roof 19.

Next, the hydraulic cylinder 38 of the prop unit 12 is actuated to move the roof member 34 in a downhill direction to disengage the same from the mine roof 19. This releases the prop unit 12 for contracting movement in a forward direction into the working space 15. By supplying pressure fluid to the forward end of the hydraulic cylinder 52 through the conduit 59, the cylinder member will be advanced relative to the piston 55 to thereby advance the prop unit 12 in the working space 15 by sliding of the floor member 33 along the mine floor 17.

By repeating the series of operating steps just explained, the prop device 10 can be moved for any desired distance in either a forward or backward direction and when it arrives at the desired location, both of the prop units 11 and 12 can be actuated to engage the roof members 18 and 34 in supporting engagement with the mine roof 19.

From the foregoing detailed description and the accompanying drawings, it will now be readily understood that this invention provides a mine roof prop device which is of a relatively simple construction embodying a comparatively small number of parts, but which is nevertheless very rugged and durable and can be readily actuated to its roof supporting condition or to disengage the same from the mine roof. It will now also be understood that the novel roof prop provided by this invention is a self-propelled prop which is movable with a step-by-step movement in either a forward or backward direction to locate the device in a desired position at which the mine roof is to be supported. Additionally, it will be seen that the jacks comprising the prop units embody an actuating means which includes inclined wedging surfaces in sliding engagement with each other and power means for causing such relative sliding.

It will now also be recognized that by reason of the ease and rapidity with which the prop units can be engaged or disengaged with respect to the mine roof and the facility with which this prop device can be shifted into or out of a desired position, the device will permit the more rapid carrying out of desired mining operations and will permit roof props to be rapidly advanced with the progress of the mining operation.

Although the mine roof prop of this invention has been illustrated and described herein to a somewhat detailed extent it will be understood, of course, that the invention is not to be regarded as being limited correspondingly in scope but includes all changes and modifications coming within the terms of the claims hereof.

Having thus described my invention, I claim:

1. In a mine roof prop of the character de-

scribed, a pair of adjacent prop units movable relative to each other along the mine floor and each having a substantially wedge-shaped movable member engageable with the mine roof and an actuating means for said movable member for engaging the same with the mine roof or disengaging the same therefrom, connecting means connecting said prop units and effective to transmit pushing and pulling forces therebetween for causing the relative movement between the prop units, and power means effective through said connecting means and operable to produce said pushing and pulling forces.

2. In a mine roof prop of the character described, a pair of adjacent prop units movable relative to each other along the mine floor, one of said prop units comprising a pair of laterally spaced jacks and the other of said prop units comprising a jack disposed between said spaced jacks, each of said jacks having a substantially wedge-shaped movable member engageable with the mine roof and an actuating means for moving said movable member into and out of engagement with said roof, and connecting means connecting said prop units and effective to transmit pushing and pulling forces therebetween for causing the relative movement between the prop units and including power means operable to produce said pushing and pulling forces.

3. In a mine roof prop of the character described, a pair of adjacent prop units movable relative to each other along the mine floor, connecting means connecting said prop units and effective to transmit pushing and pulling forces therebetween for causing such relative movement between the prop units, each of said prop units comprising a floor engaging member and a roof engageable member, an actuating means for the roof engageable member of each prop unit comprising cooperating inclined wedging surfaces and means for producing relative movement between said wedging surfaces, and power means embodied in said prop and effective through said connecting means and being operable to produce said pushing and pulling forces.

4. In a mine roof prop of the character described, a pair of adjacent prop units movable relative to each other along the mine floor, connecting means connecting said prop units and effective to transmit pushing and pulling forces therebetween for causing such relative movement between the prop units, power means operable to produce said pushing and pulling forces, each of said prop units comprising a floor engaging member and a roof engageable member paired therewith and such paired floor and roof members having cooperating inclined wedging surfaces on their adjacent faces, and means associated with each of said prop units for producing relative movement between its wedging surfaces for moving the roof member thereof into and out of engagement with the mine roof, the last-mentioned means for each prop unit comprising relatively movable parts connected respectively with the paired members of such prop unit.

5. In a self-propelled mine roof prop device, a pair of adjacent prop units each comprising a generally wedge-shaped mine floor engaging member and a generally wedge-shaped mine roof engageable member with said roof engageable member being supported by and movable relative to said floor engaging member, and actuating means for the roof engageable member of each of said prop units, said prop units being reciprocably movable relative to each other and along said

mine floor as a step-by-step advance movement of the prop device in response to alternate pushing and pulling forces transmitted between said prop units, and connecting means connecting said prop units for said relative movement and including power means for producing said pushing and pulling forces.

6. In a self-propelled mine roof prop device, a prop unit comprising a pair of spaced jacks, a second prop unit comprising a single jack disposed between said spaced jacks, each of said jacks comprising a substantially wedge-shaped mine floor engaging member and a substantially wedge-shaped mine roof engageable member with said roof engageable member being supported by and movable relative to said floor engaging member, an actuating means for the roof engageable member of each of said jacks, said prop units being reciprocably movable relative to each other and along said mine floor as a step-by-step advance movement of the prop device in response to alternate pushing and pulling forces transmitted between said prop units, transverse bar means adjacent one end of the prop device, means connecting the floor engaging members of said spaced jacks with the end portions of said bar means, and a reciprocably operable power cylinder device connecting the floor engaging member of said single jack with the intermediate portion of said bar means and being effective to produce said pushing and pulling forces.

7. In a self-propelled mine roof prop device, a prop unit comprising a pair of spaced jacks, a second prop unit comprising a single jack disposed between said spaced jacks, each of said jacks comprising a mine floor engaging member and a mine roof engageable member and a reciprocably operable power cylinder device having its ends connected with such floor and roof members and adapted to cause relative movement therebetween.

5 said floor and roof members having cooperating inclined wedging surfaces on their adjacent faces, said prop units being reciprocably movable relative to each other and along said mine floor as a step-by-step advance movement of the prop device in response to alternate pushing and pulling forces transmitted between said prop units, transverse bar means adjacent one end of the prop device, means connecting the floor engaging members of said spaced jacks with the end portions of said bar means, and a reciprocably operable power cylinder device connecting the floor engaging member of said single jack with the intermediate portion of said bar means and being effective to 10 produce said pushing and pulling forces.

15

8. A mine roof prop as defined in claim 3 in which said floor engaging member and said roof engageable member are in the form of wood timbers.

20 9. A mine roof prop as defined in claim 3 in
which said floor engaging member and said roof
engageable member are in the form of wood
timbers, and in which said cooperating inclined
wedging surfaces are formed by adjacent surfaces
25 of said timbers.
